(57) **CLAIM**

The ornamental design for a furniture trim and leg component, as shown and described.

DESCRIPTION

FIG. 1 is a front elevational view of a furniture trim and leg component showing my new design.

FIG. 2 is a perspective view thereof.

FIG. 3 is another front elevational view thereof.

FIG. 4 is a right side elevational view thereof.

FIG. 5 is a left side elevational view thereof; and,

FIG. 6 is a rear elevational view thereof.

The broken lines in FIG. 1 are for illustrative purposes only and form no part of the claimed furniture trim and leg component.
